(57) **CLAIM**

The ornamental design for a uterus stent, as shown and described.

DESCRIPTION

FIG. 1 is a front view of the design for a uterus stent showing the first embodiment;

FIG. 2 is a rear view thereof;

FIG. 3 is a left view thereof;

FIG. 4 is a right view thereof;

FIG. 5 is a top view thereof;

FIG. 6 is a bottom view thereof; and

FIG. 7 is a perspective view thereof;

FIG. 8 is a front view of the design for a uterus stent showing the second embodiment;

FIG. 9 is a rear view thereof;

FIG. 10 is a left view thereof;

FIG. 11 is a right view thereof;

FIG. 12 is a top view thereof;

FIG. 13 is a bottom view thereof; and

FIG. 14 is a perspective view thereof;

FIG. 15 is a front view of the design for a uterus stent showing the third embodiment;

FIG. 16 is a rear view thereof;

FIG. 17 is a left view thereof;

FIG. 18 is a right view thereof;

FIG. 19 is a top view thereof;

FIG. 20 is a bottom view thereof; and

FIG. 21 is a perspective view thereof;

FIG. 22 is a front view of the design for a uterus stent showing the fourth embodiment;

FIG. 23 is a rear view thereof;

FIG. 24 is a left view thereof;

FIG. 25 is a right view thereof;

FIG. 26 is a top view thereof;

FIG. 27 is a bottom view thereof; and,

FIG. 28 is a perspective view thereof.

1 Claim, 28 Drawing Sheets
